Term of patent 14 years

(Cl. D67—4)

FIG. 1

FIG. 2

Fig. 1 is a perspective view of a water cooling and dispensing combination showing my design; and

Fig. 2 is a top plan view of the water cooling and dispensing combination shown in Fig. 1.

The characteristic features of the design reside in the portions shown in full lines in the drawing.

The vertical walls opposite those shown are substantially the same as those shown and the rear walls are conventional.

I claim:

The ornamental design for a water cooling and dispensing combination, substantially as shown and described.
